F. A. Giles, of New York, N.Y.

Letters Patent No. 2266-Dated May 27-1866.

Design for the top plate of a watch.

The schedule referred to in these Letters Patent and making part of the same.

It all whom it may concern:

Be it known that I, Frederick A. Giles, of the City, County and State of New York, have invented a new design for the Top Plate of a Watch; and I, this day, declare that the following is a full, clear and exact description of the same, reference being had to the accompanying drawing forming part of this specification, said drawing representing a plan view of a watch with the cap, balancecock and balance removed to show the design of the plate A, which is tinted yellow to distinguish it from the other parts.

This plate A, is flat and of the form of a circle except that in one side of it, there is a circular recess a, which conforms to the exterior circumference of the spring-barrel B. and the interior line of which unites with the line of the outer circumference of the plate by two salient curves b, c. At a short distance from the centre e, of the plate and nearly opposite to the recess a, there is a small circular hole d, concentric with the position of the balance-staff; and between this hole d, and the nearest portion of the circular margin of the plate, there is an opening f, g. a. h. i. j. m. m. the sides f, g. of which are nearly radial to the centre of the hole d, except that on one side, there is a rounded projection, p, the exterior of which is com-

DES. 2266

2 concentric with the hole k for the staff of the lever, and on the opposite side g, there is a recess i opposite the hole h, for the spindle of the escape wheel. The inner end, h, of the said opening is curved and concentric with the hole d, and the outer end has a salient curve j, concentric or nearly so with the basking-pin and uniting with the sides by two re-entering curves m, m.

What I claim and desire to secure by letters patent is

The design and configuration of the plate A, of a watch, substantially as herein described and represented in the accompanying drawing.
